[57] CLAIM

The ornamental design for a curtain rod, as shown and described.

DESCRIPTION

FIG. 1 is a perspective showing my new design for a curtain rod;

FIG. 2 is a front perspective view thereof on an enlarged scale with the central rod broken to illustrate variable length between the finial portions thereof;

FIG. 3 is a front elevational view of FIG. 2, the rear elevational view being identical thereto;

FIG. 4 is a top view of FIG. 2, the bottom view being identical thereto;

FIG. 5 is a right side elevational view of FIG. 2, the left side elevational view being identical thereto;

FIG. 6 is a side perspective view of the finial portion removed from the rod;

FIG. 7 is a front elevational view of FIG. 6 the rear elevational view being the mirror image thereof;

FIG. 8 is a top elevational view of FIG. 6, the bottom elevational view being the mirror image thereof;

FIG. 9 is a right side elevational view of FIG. 6; and,

FIG. 10 is a side elevational view of FIG. 6.

The finial portion of the curtain rod has been shown detached for clarity of illustration.

The broken line showing of a frame, support arms and curtains in FIG. 1 is for illustrative purposes and forms no part of the claimed design.
